UNITED STATES PATENT OFFICE.

WILLIAM F. BOSTOCK, OF PROVIDENCE, RHODE ISLAND.

METHOD OF APPLYING PROTECTORS TO SHOES.

1,103,170.

Specification of Letters Patent.

Patented July 14, 1914.

Application filed August 9, 1913. Serial No. 784,005.

To all whom it may concern:

Be it known that I, WILLIAM F. BOSTOCK, a citizen of the United States, and resident of Providence, in the county of Providence and State of Rhode Island, have invented certain new and useful Improvements in Methods of Applying Protectors to Shoes, of which the following is a specification.

The object of the present invention is to produce a finished shoe equipped with protecting means at the toe portion which will efficiently protect the toe part of the sole from wearing out as long as any capacity for wear is left in other parts of the shoe, even under the most severe usage, such for instance, as is given by boys; which will not injure floors, etc., on which the wearer may walk, or cause any discomfort to the wearer; to a shoe in which the sole is attached by stitching, and which will not detract in the least from the desirable appearance of the shoe.

My invention consists both in the shoe itself, which has advantages and novel features over the prior art, as hereinafter set forth, and in the method of operation which results in the improved shoe, and which is the only method so far as I know by which the improved shoe having the desired characteristics can be produced.

In the accompanying drawings wherein I have illustrated a possible embodiment of my invention, Figure 1 represents a plan view of the bottom of a shoe, having my improved protection provided at the toe end of its sole, and Fig. 2 is a longitudinal section of the shoe on the line 2—2 of Fig. 1. Fig. 3 represents a perspective view of a part of the toe portion of the shoe to which the protector is applied, the latter being broken away to show the scored part of the sole.

The same reference characters indicate the same parts in all the figures.

Referring to the drawings *a* represents the upper of a shoe, *b* represents the inner sole, *c* represents the outer sole, *d* represents the welt and *e* represents a protector by which the wear at the toe of the shoe is reduced.

An important feature of the invention is that the protector is used in connection with a shoe having its sole secured by stitching, either to a welt as in the Goodyear type of shoe, or to an inner sole, as in the McKay type. Another important feature is that

the protecting device is so combined with the sole that it does not project from the sole at any point, either at the edges or from the bottom, but is practically flush with the sole and forms a part of the tread surface thereof. Thus the improved shoe combines the features of a stitched shoe having a protector flush with the tread surface of its sole. In order to produce this result I have had to invent a new improvement in the method of shoemaking. I will now describe this new and improved method before proceeding with the description of the shoe.

My method does not involve any change in the preliminary steps or lasting of the shoe, but commences with the shoe after it has been lasted and is ready for the sole to be applied. After being lasted the sole is laid on the bottom of the lasted shoe, by the usual or any other method and its edges are rounded, also by any known method or otherwise. Then the part of the sole which is to receive the protector is cut away to a depth substantially equal to the thickness of the protector and over an area substantially equal to the area thereof. If the protector is a plate of uniform thickness, the cut away part of the sole is of substantially uniform depth. Then the cut away part is cut in the line where the attaching stitches are laid, so as to make a groove to receive such stitches. The next step is to stitch the outer sole to the welt, in the case of a Goodyear shoe, or through to the inner sole in the case of a McKay shoe, the stitches being drawn down into the groove *f* formed in the cut away part of the sole, and having the appearance somewhat as shown in Fig. 1. When the stitches are thus pulled tight, they are approximately flush with the bottom of the cut away part of the sole. Then the protector plate is applied to the sole, such plate being approximately of the dimensions of the cut away area, and it is attached by rivets or nails *g* which pass through the plate and the sole. These rivets or nails are arranged in lines substantially parallel with the edges of the plate, those nails which lie near the edges of the sole being driven in at an inclination as shown in Fig. 2, while those near the edge of the plate which crosses the sole may be driven more nearly perpendicular. In driving the nails their inner ends are spread out so as to clinch over the inner sole, through which they pass. Thereby the protector is secured in an ex-

ceedingly rigid and permanent manner, where it will remain until the shoe is completely worn out. Then the outer edges of the protector are ground to bring them into exact conformity with the edges of the shoe sole, and finally the sole is trimmed, bur-nished, and finished in any desired way.

To increase the permanence of union of the protector plate, the same is so formed 10 when the holes for the attaching nails are made that the stock around the holes is bent up in the form of a bur h instead of being cut cleanly out. That is, the perforating of the plate is done by a tool which forces aside 15 the stock rather than removes a punching, and thus each hole is surrounded by a raised rim, which surrounds the attaching nail and is embedded in the sole. Thereby the amount of wear which the protector can 20 withstand before the nails become loosened and before it separates from the nails, is augmented.

The shoe protected according to my novel and improved method has the advantages 25 that the toe is protected so that it will not wear out before other parts of the shoe, even when subjected to hard usage as given by growing boys, it is inconspicuous and does not mar the handsome appearance and finish 30 of the shoe; it is flush with the bottom of the sole and is therefore incapable of injury to floors, carpets or the like, neither is it liable to cause discomfort to the wearer, that is, it is free from the defects which exist 35 in connection with protectors applied wholly on the outside of the sole. Finally the protector is combined with a stitched shoe, producing a combination which has never been developed before to the best of my knowledge 40 and belief.

What I claim and desire to secure by Letters Patent is:—

1. The method of producing a shoe having a sole protected at the toe, which consists in laying and rounding the sole, cutting away the tread face of the sole at and near the toe, stitching the sole, and placing a protector plate in the cut away part of the sole and over the stitches, the plate having a 45 thickness substantially equal to the depth of the cut, so that its outer face is approximately flush with the tread face of the sole.

2. The method of producing a shoe having a sole protected at the toe, which consists in 50 laying and rounding the sole, cutting away the tread face of the sole at and near the toe,

stitching the sole, placing a protector plate in the cut away part of the sole and over the stitches, the plate having a thickness substantially equal to the depth of the cut, so 60 that its outer face is approximately flush with the tread face of the sole and finishing the edges of said plate to register with the edges of the sole.

3. The method of producing a shoe having a sole protected at the toe, which consists in laying and rounding the sole, cutting away the tread face of the sole at and near the toe, stitching the sole, placing a protector plate in the cut away part of the 70 sole and over the stitches, the plate having a thickness substantially equal to the depth of the cut, so that its outer face is approximately flush with the tread face of the sole and securing said plate to the sole by nails 75 passing through the sole.

4. The method of producing a stitched shoe having a sole protected at the toe which consists in laying an outer sole upon the bottom of the shoe, cutting away the sole at 80 and near the toe to a depth less than the thickness of the sole, stitching the sole to the shoe, placing a protector plate in the recess formed by cutting away the sole, such plate having a thickness substantially equal 85 to the depth of the cut away recess, securing the plate to the sole, and finishing the edges of the plate and sole.

5. The method of producing a stitched shoe having a sole protected at the edge 90 which consists in cutting away the tread face of the sole at the point where a protector is to be applied, to a depth substantially equal to that of the protector and less than the thickness of a single piece of sole 95 leather, providing a stitch-receiving groove in the bottom of the cut away part, stitching the sole to the shoe, and laying the stitches which traverse the cut away part of the sole in such groove, whereby such 100 stitches are caused not to project from the bounding surface of the cut away part, and finally mounting a protector plate in said cut away part and over the stitches in said groove.

In testimony whereof I have affixed my signature, in presence of two witnesses.

WILLIAM F. BOSTOCK.
